COMBINED SOFA BED AND TABLE UNIT

Chester A. Pink, 351 Moraine, Highland Park, Ill.

Filed Oct. 26, 1960, Ser. No. 62,627

Term of patent 14 years

(Cl. D5—4)

FIG. 1 is a perspective view showing a combined sofa bed and table unit embodying my design; and

FIG. 2 is a plan view of the combined sofa bed and table unit embodying my design.

The dominant features of my design are shown in full lines with the back of the combined sofa bed and table unit being conventional; and a characteristic feature of my design resides in the raised side edge portions of the table complementing the tops of the bolster boxes and joined by a triangular corner portion cooperating to present the diamond shaped table surface, all as shown.

I claim:

The ornamental design for a combined sofa bed and table unit, substantially as shown and described.
